MINE CAR SEALING DEVICE

Hugh W. Sanford, Jr., and Alfred F. Sanford, II,
Knoxville, Tenn., assignors to The Sanford In-
vestment Company, Wilmington, Del., a corpo-
ration of Delaware

Application December 23, 1947, Serial No. 793,398

12 Claims. (Cl. 105—253)

1

This invention relates to improvements in mine car sealing devices, particularly for sealing the drop bottom doors of mine cars used for transporting coal or other materials from a loading point to a point of discharge, where such materials are discharged through the bottom of the car upon release of the drop bottom doors therein.

In mine cars used for the transportation of coal and other loose lading, it is important that the drop bottom doors be sealed at the opposite edges thereof against the leakage of coal between the edges of the doors and the side sills of the car. It is difficult to form the doors so these will fit so closely to the inside faces of the side sills as to prevent the leakage of loose coal therebetween. Consequently, special provision should be made for sealing the space between the edges of the doors and the side sills against the leakage of coal therebetween.

The object of this invention is to improve the construction of mine cars, especially of large capacity, and particularly the means for sealing the lateral edges of the drop bottom doors, whereby a wide door opening will be sealed effectively at its lateral edges when the door is closed against the leakage of coal therethrough.

This object may be accomplished, according to certain embodiments of this invention, by the provision of means provided in cooperating relation with the edge of the door and the adjacent portion of the car structure in wiping relation with the opposed surfaces therebetween for sealing effectively the crack therebetween at each opposite edge of the door and without interfering with the normal opening and closing actions of the latter. Such a wiping action can be accomplished in various ways, as, for instance, by a flexible or yieldable element supported by one of the cooperating members in position to overlap or bear upon the other to prevent the leakage of coal or loose lading through the crack.

Certain embodiments of the invention are illustrated in the accompanying drawings, in which:

Fig. 1 is a side elevation of a mine car showing the invention applied thereto;

Fig. 2 is a detail transverse section through a portion of the car on the line 2—2 of Fig. 1, showing one form of sealing means for the edge of the door; and

Figs. 3 to 11 are similar views showing other forms of sealing means that may be used.

The invention is shown as applied to a mine car of the four-wheel type adapted to travel on

2

a track formed by rails R. The car is shown as comprising a body having side and end walls 1 and 2 supported on side sills 3, at each opposite side of the body. The frame structure of the car comprising the side sills 3 and the combined end sills and bumpers 4, is supported on wheels 5, adapted to travel on the track R.

The car illustrated is of the bottom dumping type, the space between the side sills 3 being open, except as it is closed by drop bottom doors generally designated 6, three of which are shown. These doors 6 are latched in closed positions and are adapted to be released to discharge the lading from the car.

15 Each door 6 extends from side-to-side of the lading body between the opposed side sills 3, with a crack between each edge of the door 6, and the adjacent side sill, as will be evident in the drawings. Usually each edge of the door 6 is provided with a flange on the edge thereof, either formed integral with the door plate or separate, as shown, and indicated at 7 in Fig. 2. In this form, the flange bar 7 extends lengthwise of the door plate and is welded thereto. Preferably a substantially straight bar may be used for the purpose, the door 6 also being substantially straight and plane throughout the major portion of its length. This flange bar 7 at each edge of the door 6 is adapted to extend up into the space between the opposed side sills when the door is in closed position. Usually the doors are closed by closing devices mounted in the track R, and are latched at their free edges. This requires the upward movement of the doors to points above the closed positions thereof in the latching or unlatching of the doors.

20 In the hauling of coal or other loose lading, the latter often sifts out through the cracks provided between the door and the adjacent side sill unless provision is made to seal the space between the edges of the door and the sill. Several forms of sealing devices are illustrated, which preferably have some wiping action with the opposed members and overlapping the space therebetween. Such wiping action tends to seal the space while allowing the relative movement between the parts necessary for the opening and closing movements of the door and the latching and unlatching thereof.

25 In the form shown in Fig. 2, this sealing means is provided by a leaf spring, generally designated at 8, which may be formed of a strip of spring steel extending lengthwise throughout the length of the side sill 3, or the door 6, and attached at 9, as by welding, riveting or any other suitable

manner, to the adjacent under edge of the side sill 3. The strip 8 at its upper inner edge bears in overlapping relation with the upper edge of the flange bar 7 on the door 6, at each opposite edge of the latter, and overlapping the space between these parts, prevents the lading from sift-
ing through the crack therebetween. As the spring strip 8 bears in wiping relation with the adjacent edge of the door 6, or the flange bar 7 thereof, this strip 8 will yield to permit relative upward and downward movement of the door with respect to the side sill, while maintaining the sealing relation whenever the door is in closed position.

This sealing spring may be shortened as indicated at 10, in Fig. 4, if desired, so as to have wiping relation with the face of the strip 7, instead of with the upper edge thereof, as in Fig. 2.

Another form thereof is shown in Fig. 5, as indicated at 11, also bearing against the face of the door flange 7, but folded over in U-shape with the wiping edge intermediate the width of the spring strip. The lower edge of the strip 11 is secured rigidly to the side sill 3, while the upper edge thereof is free but bears against the inner face of the sill, so as to yield in wiping relation with the adjacent face of the flange 7.

In Figs. 3 and 6, are shown the use of brushes in wiping action between the adjacent portions of the door and the side sill. Fig. 3 shows a brush 12 secured to the under face of the side sill 3, and preferably formed as a wire brush with the wire bristles relatively close together in position for wiping action with the lateral face of the flange 7. In Fig. 6, the wire brush 13 is supported directly upon the inner face of the side sill 3, in wiping relation with the lateral face of the flange bar 7.

In Figs. 7 and 8, the sealing member is carried by the door. In Fig. 7, the sealing member 25 is in the form of a leaf spring secured at one edge to the flange bar 7 of the door, while its opposite edge is in wiping relation with the under edge of the side sill 3. In Fig. 8, the sealing member 26 is secured over the upper edge of the flange bar 7 and also extends into wiping relation with the lower edge of the side sill. In each of these instances, the wiping member is composed of a strip of spring steel, or other metallic material suitable for the purpose.

In Fig. 11, the wiping member is shown at 27 secured to the upper edge of the flange bar 7 and extends upwardly therefrom in wiping relation with the inner face of the side sill 3, overlapping the crack between the sill and the door.

In Figs. 9 and 10, the wiping member is provided in the form of a rubber gasket in or over the crack extending lengthwise of each edge of the door. This gasket is shown in Fig. 9, at 28, carried by the inner face of the side sill 3, and is in position to bear upon the outer face of the door flange 7. In Fig. 10, the gasket 29 is carried by the door flange 7 and bears against the inner face of the side sill 3.

In each instance, it will be clear that the sealing means provided is at each lateral edge of the door and extends throughout the major portion of the length of the door, at least between the wheel hoods generally designated at 5' in Fig. 1. The edges of the door inwardly with respect to the adjacent faces of the hoods 5' may be closed by means of deflector plates, if desired, as set forth more in detail in the application of Hugh W. Sanford, for Mine Car Sealing Devices, Serial No. 739,796, filed April 7, 1946, which has matured

to Patent Number 2,577,040, dated December 4, 1951.

While the invention has been illustrated and described in several embodiments, it is recognized that variations and changes may be made therein, without departing from the invention, except as specified in the claims.

We claim:

1. In a vehicle having a lading body with separated side sill structures and having a bottom opening therebetween for the discharge of lading therethrough, a drop bottom door for closing said opening and having cracks between opposing faces on said edges of the door and the side sill structures, means mounting an edge portion of the door on the vehicle for swinging movement about an axis extending transversely of the vehicle, movable means for engaging the opposite edge portion of the door for holding the door closed and movable to release the door for opening, said door being movable on the mounting means relative to the side sill structure to a point above the closed position thereof for movement of the engaging means into holding position relative thereto, and means for closing the crack between the door and each adjacent side sill structure, including a resilient member carried by one of said elements in position to engage the opposing face of the other of said elements in wiping relation during the closing movement of the door relative to the side sill structures, said resilient member being arranged to vary the coacting wiping pressure on the adjacent element in different positions of the door.
2. In a vehicle having a lading body with separated side sill structures and having a bottom opening therebetween for the discharge of lading therethrough, a drop bottom door for closing said opening and having cracks between opposing faces on said edges of the door and the side sill structures, means mounting an edge portion of the door on the vehicle for swinging movement about an axis extending transversely of the vehicle, movable means for engaging the opposite edge portion of the door for holding the door closed and movable to release the door for opening, said door being movable on the mounting means relative to the side sill structure to a point above the closed position thereof for movement of the engaging means into holding position relative thereto, and means for closing the crack between the door and each adjacent side sill structure, including a resilient member carried by one of said elements in position to engage the opposing face of the other of said elements in wiping relation during the closing movement of the door relative to the side sill structures, said resilient member extending in overlapping relation with the crack from side-to-side thereof, said resilient member being arranged to vary the coacting wiping pressure on the adjacent element in different positions of the door.
3. In a vehicle having a lading body with separated side sill structures and having a bottom opening therebetween for the discharge of lading therethrough, a drop bottom door for closing said opening and having cracks between said edges of the door and the side sill structures, means mounting an edge portion of the door on the vehicle for swinging movement about an axis extending transversely of the vehicle, movable means for engaging the opposite edge portion of the door for holding the door closed and movable to release the door for opening, said door being movable on the mounting means relative to the

side sill structure to a point above the closed position thereof for movement of the engaging means into holding position relative thereto, and means for closing the crack between the door and each adjacent side sill structure, including a member carried by the side sill structure in position to engage the adjacent edge of the door and extending transversely of the crack therebetween during the closing of the door.

4. In a vehicle having a lading body with separated side sill structures and having a bottom opening therebetween for the discharge of lading therethrough, a drop bottom door for closing said opening and having cracks between opposing faces on said edges of the door and the side sill structures, means mounting an edge portion of the door on the vehicle for swinging movement about an axis extending transversely of the vehicle, movable means for engaging the opposite edge portion of the door for holding the door closed and movable to release the door for opening, said door being movable on the mounting means relative to the side sill structure to a point above the closed position thereof for movement of the engaging means into holding position relative thereto, and means for closing the crack against the leakage of lading therethrough, including a member carried by the door at the edge thereof in overlapping relation with the crack and in position to engage the opposing face of the adjacent side sill structure during the closing movement of the door.

5. In a vehicle having a lading body with separated side sill structures and having a bottom opening therebetween for the discharge of lading therethrough, a drop bottom door for closing said opening and having cracks between opposing faces on said edges of the door and the side sill structures, means mounting an edge portion of the door on the vehicle for swinging movement about an axis extending transversely of the vehicle, movable means for engaging the opposite edge portion of the door for holding the door closed and movable to release the door for opening, said door being movable on the mounting means relative to the side sill structure to a point above the closed position thereof for movement of the engaging means into holding position relative thereto, and means for closing the crack against the leakage of lading therethrough, including a member carried by the door at the edge thereof in overlapping relation with the crack and in position to engage the adjacent side sill structure during the closing movement of the door, said means being constructed of resilient material and engaging in wiping relation against the opposing face of an edge portion of the side sill structure, said resilient member being arranged to vary the coacting wiping pressure on the adjacent element in different positions of the door.

6. In a vehicle having a lading body with separated side sill structures and having a bottom opening therebetween for the discharge of lading therethrough, a drop bottom door for closing said opening and having cracks between said edges of the door and the side sill structures, means mounting an edge portion of the door on the vehicle for swinging movement about an axis extending transversely of the vehicle, movable means for engaging the opposite edge portion of the door for holding the door closed and movable to release the door for opening, said door being movable on the mounting means relative to the side sill structure to a point above the closed

position thereof for movement of the engaging means into holding position relative thereto, and means for closing the crack between the door and each adjacent side sill structure, including a member carried by the side sill structure in position to engage the adjacent edge of the door and extending transversely of the crack therebetween during the closing of the door, said means being constructed of resilient material and engaging in

5 wiping relation against an edge portion of the door, said resilient member being arranged to vary the coacting wiping pressure on the adjacent element in different positions of the door.

7. In a vehicle having a lading body with separated sill structures and having an opening therebetween for the discharge of lading therethrough, a door for closing said opening and having cracks between opposing faces on said edges of the door and the sill structures, means

10 mounting an edge portion of the door on the vehicle for swinging movement about an axis extending transversely of the vehicle, movable means for engaging the opposite edge portion of the door for holding the door closed and movable

15 to release the door for opening, said door being movable on the mounting means relative to the side sill structure to a point above the closed position thereof for movement of the engaging means into holding position relative thereto, and means

20 for closing the crack between the door and each adjacent sill structure, including a resilient member carried by one of said elements in position to engage the opposing face of the other of said elements in wiping relation during the closing movement of the door relative to the sill structures,

25 said resilient member being arranged to vary the coacting wiping pressure on the adjacent element in different positions of the door.

8. In a vehicle having a lading body with

30 separated sill structures and having an opening therebetween for the discharge of lading therethrough, a door for closing said opening and having cracks between opposing faces on said edges of the door and the sill structures, means mounting an edge portion of the door on the vehicle for swinging movement about an axis extending transversely of the vehicle, movable means for

35 engaging the opposite edge portion of the door for holding the door closed and movable to release the door for opening, said door being movable on the mounting means relative to the side sill structure to a point above the closed position thereof for movement of the engaging means into holding position relative thereto, and means for

40 closing the cracks between the door and the sill structures and forming a wiping action therebetween in the closing movement of the door, said closing means comprising a cantilever leaf spring fixed at one edge to one of said members and having the opposite edge thereof free in wiping

45 relation with the opposing face of the other of said members, said leaf spring being arranged to vary the pressure on the adjacent element in wiping relation therewith in different positions

50 of the door.

9. In a vehicle having a lading body with separated sill structures and having an opening therebetween for the discharge of lading therethrough, a door for closing said opening and having cracks between opposing faces on said edges of the door and the sill structures, means mounting an edge portion of the door on the vehicle for swinging movement about an axis extending transversely of the vehicle, movable means for

55 engaging the opposite edge portion of the door for

holding the door closed and movable to release the door for opening, said door being movable on the mounting means relative to the side sill structure to a point above the closed position thereof for movement of the engaging means into holding position relative thereto, and means for closing the cracks between the door and the sill structures and forming a wiping action therebetween in the closing movement of the door, said closing means comprising a cantilever leaf spring fixed at one edge to the edge of the door and having the opposite edge thereof free in wiping relation with the opposing face of the sill structure, said leaf spring being arranged to vary the pressure on the adjacent element in wiping relation therewith in different positions of the door.

10. In a vehicle having a lading body with separated side sill structures and having an opening therebetween for the discharge of lading therethrough, a plurality of drop bottom doors between the side sill structures for closing said opening and having cracks between opposing faces on the lateral edges of the doors and the sill structures, means mounting an edge portion of each of the doors for swinging movement about an axis extending transversely of the vehicle and with adjacent edge portions in overlapped relation in supported positions, one of the doors being movable on the mounting means relative to the side sill structures above the lower edges thereof to a point appreciably above the closed position thereof, and a resilient member carried by each door adjacent a lateral edge thereof in position to engage the opposing face of the adjacent side sill structure in wiping relation therewith during the closing movement of the door for preventing leakage of lading therethrough, said resilient member being arranged to vary the co-acting wiping pressure on the adjacent element in different positions of the door.

11. In a vehicle having a lading body with separated side sill structures and having an opening therebetween for the discharge of lading therethrough, a plurality of drop bottom doors between the side sill structures for closing said opening and having cracks between opposing faces on the lateral edges of the doors and the sill structures, means mounting an edge portion of each of the doors for swinging movement about an axis extending transversely of the vehicle and with adjacent edge portions in overlapped relation in supported positions, one of the doors being movable on the mounting means relative to the side sill structures above the lower edges thereof to a point appreciably above the closed position thereof, and a leaf spring carried by each door adjacent each lateral edge thereof in position for wiping relation with the opposing face

of the adjacent side sill structure during the closing movement of the door relative thereto for preventing leakage of lading therethrough, said leaf spring being arranged to vary the pressure on the adjacent element in wiping relation therewith in different positions of the door.

12. In a vehicle having a lading body with separated side sill structures and having an opening therebetween for the discharge of lading therethrough, a plurality of drop bottom doors between the side sill structures for closing said opening and having cracks between opposing faces on the lateral edges of the doors and the sill structures, means mounting an edge portion of each of the doors for swinging movement about an axis extending transversely of the vehicle and with adjacent edge portions in overlapped relation in supported positions, one of the doors being movable on the mounting means relative to the side sill structures above the lower edges thereof to a point appreciably above the closed position thereof, and a leaf spring carried by each door adjacent each lateral edge thereof in position for wiping relation with the opposing face
